UNITED STATES PATENT OFFICE.

ROBERT LEE BREWER, OF CAMDEN, ARKANSAS.

RAILWAY-SWITCH.

No. 922,661.

Specification of Letters Patent.

Patented May 25, 1909.

Application filed November 25, 1907. Serial No. 403,715.

To all whom it may concern:

Be it known that ROBERT LEE BREWER, a citizen of the United States, residing at Camden, in the county of Ouchita and State of 5 Arkansas, has invented certain new and useful Improvements in Railway-Switches, of which the following is a specification.

This invention relates to railway switches and more particularly to safety switches, and 10 has for its object to provide a switch of this character whereby the switch rails may be automatically moved by the passing of a train from the main line and which switch rail will be automatically set after the passing 15 of the train.

Other objects and advantages will be apparent from the following description and it will be understood that changes in the specific structure shown and described may be 20 made within the scope of the claim without departing from the spirit of the invention.

In the drawings forming a portion of this specification, and in which like numerals of reference indicate similar parts in the several 25 views, Figure 1 is a top plan view of the present switch closed, Fig. 2 is a similar view showing the switch set for a siding, Fig. 3 is a vertical longitudinal sectional view on the line 4—4 of Fig. 1, Fig. 4 is a cross sectional 30 view on the line 5—5 of Fig. 1, Fig. 5 is a horizontal sectional view on the line 6—6 of Fig. 4, Fig. 6 is a sectional view on the line 7—7 of Fig. 1.

Referring now more particularly to the 35 drawings, there is shown a railway switch 10, consisting of main line rails 11 and 12, and siding rails 13 and 14. The rail 11 of the main line is stationary, and the rail 12 is movable. The rail 13 is also a movable rail 40 and is connected to the rail 12 by means of the movable members 15 and 16 respectively. The member 15 is provided with a housing block 17, recessed upon its under face as shown at 18, and is thus arranged to 45 slide upon the member 16, as shown. The housing 17 is also provided with downwardly extending guide flanges 19 and 20 which are arranged at either side of the member 16. The member 16 is provided with a recess 21, 50 receiving one end of a coiled spring 22. The other end of this spring is arranged in a recess 23 formed in the member 15.

The rail 12 is provided upon its base flange

with a downwardly extending block 24, grooved as shown at 25 to receive a slideable 55 bar 26. The bar 26 is secured to the block 24 as shown at 27, and extends outwardly of the rail 14 and beneath the same as shown, its outer end being slotted as shown at 28 and carrying pivotally one end of a link 29. The link 60 is pivoted at its opposite end to an outwardly extending finger 30 carried by a rotatable post 31. The post 31 is protected from the weather by means of a casing 32, and is provided with a hand lever 33 for operation of 65 the bar 26.

The rail 13 is provided with a downwardly extending block 34, secured to the base flange of this rail as shown. The block 34 is provided with the enlarged heads 35 and 36 re- 70 spectively and in these heads there are formed horizontally disposed recesses 37 and 38. These recesses 37 and 38 are arranged to receive one end of coiled springs 39 and 40. The opposite ends of these springs are en- 75 gaged in horizontally disposed recesses formed in the enlarged heads 43 and 44 of a block 45. The block 45 is recessed as shown at 46, and is thus arranged to straddle the bar 26, as shown, being secured thereto by 80 means of a set screw 47. The springs 39 and 40 hold the rail 13 resiliently in spaced relation with the block 45, so that when the rail 12 is disposed against the siding rail 14, the rail 13 will lie in spaced relation with the 85 rail 11, as shown in Figs. 1 and 3 of the drawings.

When a train passes the switch on the main line moving outwardly as shown by the direction of the arrow in Fig. 3, it will be seen 90 that the flanges of the wheels of the train will engage the rail 13, and by means of the sliding arrangement of this rail it will be seen that a train may pass this point without the aid of an operator for the switch, and after 95 the train has passed the point it will be seen that the rail 13 will be automatically moved to its original position. The above description also applies to a train which may be on a siding. If a train should be coming in a 100 reverse direction the rails 12 and 13 may be moved away from the rails 11 or 14 by means of the slideable bar 26 which is connected to the revolvable post 31.

It will be understood that the spring 22, 105 and the springs 39 and 40 are properly ad-

justed upon their support to balance each other for the operation of the switch as set forth.

What is claimed is:

- 5 A railway switch comprising main line rails and siding rails, one of said main line rails and one of said siding rails being resiliently coengaged in spaced relation, and means engaged centrally thereof for shifting

said coengaged rails into yieldable engagement alternately with an adjacent rail.

In testimony whereof I affix my signature, in presence of two witnesses.

ROBERT LEE BREWER.

Witnesses:

W. H. HALL,
J. T. SIFFORD.
